UNITED STATES PATENT OFFICE.

MERVYN A. DAVENPORT, OF LOS GATOS, CALIFORNIA, ASSIGNOR OF ONE-HALF TO
GEORGE F. SHANER, OF LOS GATOS, CALIFORNIA.

NURSING BOTTLE.

Application filed May 31, 1922. Serial No. 564,695.

To all whom it may concern:

Be it known that I, MERVYN A. DAVENPORT, a citizen of United States, residing at Los Gatos, county of Santa Clara, and 5 State of California, have invented new and useful Improvements in Nursing Bottles, of which the following is a specification.

This invention relates to nursing bottles for infants, and has for its object to provide an improved nursing bottle equipped 10 with means for admitting air to the interior of the bottle as the contents thereof are withdrawn through the nipple. This feature is very advantageous, as it prevents 15 a vacuum from being created in the bottle, and consequently the food will at all times flow readily with a minimum of exertion on the part of the infant.

One form which the invention may assume is exemplified in the following description and illustrated by way of example in the accompanying drawings, in which:

Fig. 1 is a view in elevation and section disclosing the preferred embodiment of the 25 invention.

Fig. 2 is a fragmentary view in elevation disclosing certain details of construction.

Referring more particularly to the drawing, 10 indicates a nursing bottle of suitable design, and which is formed at its top for the reception of a nursing nipple 12. Formed in the side of the bottle adjacent the top thereof is an aperture 14 of sufficient dimensions to receive a valve structure generally indicated at 15. This valve structure is designed to permit air to enter the bottle to replace the food drawn therefrom by an infant nursing, and it consists of a 20 valve cage 16 and a tube 17. The tube in this instance is formed as an integral part of the valve cage. As shown in Fig. 1, the valve cage is formed in two sections which are threadedly connected as at 18, and 25 which are formed with shoulders 18^a between which the wall of the bottle is clamped. Both of these sections are recessed so that when they are united a valve chamber 19 is formed. This chamber communicates 30 with the atmosphere through perforations 20 formed in the nut portion of the valve body 16 and with the interior of the bottle through perforations 21 and the open ended tube 17. Mounted in the chamber 35 19 is a ball check 22 which is adapted un-

der certain conditions to rest on a seat 23 and prevent passage of liquid food from the bottle through the perforations 20.

In use, the device is assembled as illustrated in the drawings. The bottle may then 60 be partially filled with a liquid, and a nipple positioned in place inclosing the open end of the bottle. The infant may then draw the liquid through orifices in the nipple, in the usual manner.

It is obvious that as the food is drawn from the bottle, air will enter through the perforations 20. This will prevent a vacuum from being created in the bottle and will consequently allow the liquid to flow 70 freely. However, if the bottle is upset, its contents will not emerge from the perforations 20 as the ball check will seat on the seat 23 and entirely obstruct passage of the food from the bottle to the perforations. 75

From the foregoing it is obvious that the device here disclosed, while simple in construction and operation, presents a desirable nursing bottle which is inexpensive to manufacture.

Although in the foregoing description and in the drawings, the invention has been specifically described and illustrated, I wish it understood that various changes in the construction, combination, and arrangement of 85 parts may be made by those skilled in the art, without departing from the spirit of the invention.

Having thus described my invention, what I claim and desire to secure by Letters Patent is:

1. A nursing bottle comprising a container having an open end for the reception of a nipple, said container having an opening formed in one side thereof, a valve body 95 adapted to be secured in said opening, a tube formed as an extension of said valve body and extending within the container to a point adjacent the bottom, the lowermost end of said tube being open, a passageway 100 formed in said valve body and communicating with the atmosphere and the interior of the container through the tube, a ball check in said passageway, and a valve seat formed adjacent the outer end of said passageway. 105

2. A nursing bottle comprising a container having an open end for the reception of a nursing nipple, said container having a circular opening formed in one side thereof adjacent the said open end, a two-part valve 110

- body having an interior valve chamber adapted to be positioned in said opening, annular shoulders on said parts of said valve body, and a threaded connection between 5 said parts by which the valve body may be secured to the container and in said opening, a downwardly extending tube formed as an extension of the inner part of the said valve body, the lower end of said tube being open, 10 a perforated partition between the interior of said tube and the valve chamber, a perforated partition between said chamber and the atmosphere, a valve seat formed between the last named partition and the valve chamber, and a check valve in said chamber. 15
3. A nursing bottle comprising a container having an open end for the reception of a nipple, said container having an opening formed in one wall thereof, a two-part valve 20 body adapted to be mounted in said opening, said parts of said valve body being threadedly connected and each having a shoulder whereby the valve body will be clamped to said wall and in said opening, each of said 25 parts being recessed to form a valve chamber in the valve body, a ball check in said chamber, and perforated partitions separating said chamber from the atmosphere and
- the interior of the bottle, and a seat for said ball check formed adjacent the outermost 30 partition.
4. In combination with an open ended nursing bottle, said bottle having an opening formed in one wall thereof, of a two-part valve body adapted to be mounted in said 35 opening, said parts of said valve body being threadedly connected and each having a shoulder whereby the valve body will be clamped to the bottle and in said opening, said parts of said valve body being recessed 40 to form a valve chamber when they are united, a ball check in said chamber, a tube formed as an extension of the innermost part of the valve body and extending downwardly to adjacent the bottom of the bottle, 45 a perforated partition separating the interior of the tube from the valve chamber, the outer wall of the outermost part of the valve body being perforated to provide communication between the valve chamber and the atmosphere, and a seat for said ball check formed adjacent said perforated wall whereby the ball check may stop communication between said chamber and the atmosphere. 50
